ABSTRACT OF THE DISCLOSURE

Compounds of the formula

in which R is hydrogen or alkyl; R₁ is hydrogen or alkyl; R₂ is alkyl or alkoxy; R₃ is alkoxy; R₄ is alkyl, alkenyl, alkynyl, benzyl or carbamoyloxyalkylene and the use of these compounds as insecticides and acaricides.

This invention relates to certain novel heterocyclic chemical compounds and their use as insecticide and acaricides. More particularly, the compounds are certain 3-N-substituted thiazole phosphates and phosphonates.

The compounds of this invention that are useful as insecticides and acaricides are those having the formula:

in which R is hydrogen or alkyl having 1 to 5 carbon atoms, inclusive, preferably methyl; R₁ is hydrogen or alkyl having 1 to 5 carbon atoms, inclusive, preferably methyl; R₂ is alkyl having 1 to 5 carbon atoms, inclusive, or alkoxy having 1 to 5 carbon atoms, inclusive; R₃ is alkoxy having 1 to 5 carbon atoms, inclusive; R₄ is alkyl having 1 to 5 carbon atoms, inclusive, preferably 1 to 3 carbon atoms, inclusive, alkenyl having 3 to 6 carbon atoms, inclusive, preferably 3 carbon atoms, alkynyl having 3 to 6 carbon atoms, inclusive, preferably 3 carbon atoms, benzyl, or carbamoyloxyalkylene, wherein said alkylene has 1 to 3 carbon atoms, inclusive, preferably 2 carbon atoms.

The compounds having the formula

in which R, R₁, R₂, R₃ and R₄ are as defined above can be prepared by the following reactions:

2

(c)

Equation (c), the reaction of the haloacetamide with the phosphono or phosphoro dithioic acid is an in situ reaction between a haloacetamide with a salt of an organic phosphate or phosphonate. The reaction of a haloacetamide with a salt of an organic phosphate to form an acetamido phosphate is well known:

The same general method is used in the preparation of the compounds of this invention; however, certain modifications of the above reaction have been made to simplify the procedure and to insure in most instances, improved yields. The modifications include the use of anhydrous triethylamine which obviates the isolation of the phosphate or phosphonate salt,

and dimethylformamide (DMF) as a solvent medium which facilitates and promotes the reaction.

Although other solvents such as ketones, alcohols, benzene-H₂O mixtures, etc., can be used, DMF has been found most advantageous with regard to reaction times and yields. It has also been found that a small excess of triethylamine is advantageous in bringing the reaction to completion.

After completion of the reaction between the chloroacetamide and the phosphate, or phosphonate amine salt, the product is conveniently isolated by pouring the mixture into water. If the product is a solid, it is filtered off and recrystallized if desired. If the product is a liquid, it can be extracted with a solvent such as benzene, chloroform, etc.

Chloroacetamide derivatives are used for economic reasons; however, bromo or iodoacetamides can also be used.

The compounds of the present invention and their preparation are more particularly illustrated by the following examples. Following the example is a table of compounds which are prepared according to the procedures described herein.

EXAMPLE

Preparation of the intermediate

2-imino-3-N-methylthiazole.—Fifty grams (50 g., 0.5 mole) of 2-aminothiazole, 78.1 g. (0.55 mole) of methyl iodide in 100 cc. of methanol were mixed and refluxed for 2 hours. The reaction mixture was cooled to 15° C. and filtered. The solid material was slurried in ether, filtered and washed with hexane. There was obtained 91.9 g. of product. The filtrate was evaporated, slurried in 75 cc. of boiling isopropanol, cooled and filtered. Total yield was 106.2 g. (87.6% of theory).

The solid product, supra, was dissolved in water (300 cc.). Concentrated ammonium hydroxide (40.5 g., 0.66 mole, 45 cc.) was added while maintained at a temperature below 20° C. The reaction mixture was exhaustively extracted with chloroform, dried over anhydrous mag-

nesium sulfate, filtered and the organic solvent evaporated in vacuo. There was obtained 41.9 g. (84% of theory) of the title compound. $n_D^{30}=1.5915$.

Preparation of the intermediate

2-chloroacetylmino-3-N-methylthiazole.—The intermediate 2-imino-3-N-methylthiazole (41.9 g., 0.37 mole) was added to a solution of chloroacetic anhydride (82 g., 0.48 mole) in dioxane (80 cc.). The temperature during the addition was maintained below 65° C. After addition was completed, the reaction mixture was heated to 65–72° C. for 15 minutes. It was cooled to 60° C. and 10 ml. of water added, cooled to 45° C. and ice water added. The product was filtered and washed with ice water and dried. There was obtained 42.8 g. (71.8% of theory) of the title compound, M.P. 117–120° C.

Preparation of 2-O,O-diethylphosphorodithioyl acetimino-3-N-methylthiazole.—Eleven and four-tenths grams (0.06 mole) of 2-chloroacetylmino-3-N-methylthiazole was slurried in 30 ml. of DMF to this stirred mixture was added a pre-neutralized mixture of 18.6 g. (0.1 mole) (16.4 ml.) of O,O-diethylphosphorodithioic acid dissolved in 30 ml. DMF and 10.1 g. (0.1 mole) (13.8 ml.) of triethylamine. To this stirred mixture was added an additional 2 ml. of triethylamine to make the mixture basic. The mixture was heated and stirred at 55–60° C. for two hours. After the completion of the reaction, 150–200 ml. of benzene was added and the mixture washed twice with dilute sodium chloride solution, dried over anhydrous magnesium sulfate, filtered, and the benzene evaporated. There was obtained 19.5 g. (95.6% of theory) of the title compound, a liquid, $n_D^{30}=1.5896$.

The above structure was confirmed by N.M.R. and infrared analysis.

The following is a table of compounds which are prepared according to the aforementioned procedures. Compound numbers have been assigned to them and are used for identification throughout the balance of the specification.

TABLE I

Compound number	R	R ₁	R ₂	R ₃	R ₄	M.P., °C. or n_D^{30} kal.
1	H	H	OC ₂ H ₅	OC ₂ H ₅	CH ₃	1.5896
2	H	H	C ₂ H ₅	OC ₂ H ₅	CH ₃	1.6109
3	CH ₃	H	OC ₂ H ₅	OC ₂ H ₅	CH ₃	94–95
4	CH ₃	CH ₃	OC ₂ H ₅	OC ₂ H ₅	CH ₃	117–120
5	CH ₃	H	C ₂ H ₅	OC ₂ H ₅	CH ₃	50–53
6	CH ₃	CH ₃	C ₂ H ₅	OC ₂ H ₅	CH ₃	75–77
7	CH ₃	H	C ₂ H ₅	OCH(CH ₃)	CH ₃	106–108
8	CH ₃	CH ₃	C ₂ H ₅	OCH(CH ₃) ₂	CH ₃	99–101
9	H	H	C ₂ H ₅	OCH(CH ₃) ₂	CH ₃	1.5958
10	CH ₃	CH ₃	C ₂ H ₅	OCH ₂ CH(CH ₃) ₂	CH ₃	68–70
11	H	H	CH ₃	OCH ₃	CH ₃	95–97
12	H	H	OCH ₃	OCH ₃	CH ₃	1.5944
13	H	H	C ₂ H ₅	OCH ₃	CH ₃	1.6199
14	H	H	OCH ₃	OCH ₃	CH ₂ CH=CH ₂	1.5907
15	H	H	C ₂ H ₅	OCH(CH ₃) ₂	CH ₂ CH=CH ₂	1.5863
16	H	H	C ₂ H ₅	OC ₂ H ₅	CH ₂ CH=CH ₂	1.5852
17	H	H	C ₂ H ₅	OCH ₃	CH ₂ CH=CH ₂	1.5874
18	H	H	C ₂ H ₅	OC ₂ H ₅	CH ₂ C≡CH	52–54
19	H	H	C ₂ H ₅	OCH(CH ₃) ₂	CH ₂ C≡CH	54–56
20	H	H	C ₂ H ₅	OCH ₃	CH ₂ C≡CH	1.6136
21	H	H	C ₂ H ₅	OCHCH ₂ (CH ₃) ₂	CH ₂ C≡CH	1.5823
22	H	H	C ₂ H ₅	OC ₂ H ₅	CH ₂ —	1.6146
23	H	H	C ₂ H ₅	OCH(CH ₃) ₂	CH ₂ —	1.6112
24	H	H	OC ₂ H ₅	OC ₂ H ₅	CH ₂ —	1.6035
25	H	H	C ₂ H ₅	OCH ₂ CH(CH ₃) ₂	CH ₂ —	1.5997
26	H	H	C ₂ H ₄	OCH(CH ₃) ₂	CH ₂ CH ₂ CH ₃	1.5550
27	H	H	C ₂ H ₅	OCH(CH ₃) ₂	OCH ₂ CH ₂ OCH ₂ NHCH ₃	78–82

4 INSECTICIDAL EVALUATION TESTS

The term "insect" is used herein in its broad common usage to include spiders, mites, ticks and like pests which are not in the strict biological sense classified as insects. The term "insect" is used to refer not only to those small invertebrate animals belonging mostly to the class Insecta, comprising six-legged usually winged forms, as beetles, bugs, bees, flies, and so forth, but also to other allied classes of arthropods whose members are wingless and usually have more than six legs, as spiders, mites, ticks, centipedes, and wood lice.

The following insect species were used in evaluation tests for insecticidal activity:

- 15 (1) Housefly (HF)—*Musca domestica* (Linn.)
- (2) Lygus bug (LB)—*Lygus hesperus* (Knight)
- (3) Bean aphid (BA)—*Aphis fabae* (Scop.)

The housefly (HF) was used in evaluation tests of selected compounds as insecticides by the following procedure. A stock solution containing 100 μ g./ml. of the toxicant in an appropriate solvent was prepared. Aliquots of this solution were combined with 1 milliliter of an acetone-peanut oil solution in a glass petri dish and allowed to dry. The aliquots were there to achieve desired toxicant concentration ranging from 100 μ g./per petri dish to that at which 50% mortality was attained. The petri dishes were placed in a circular cardboard cage, closed on the bottom with cellophane and covered on top with cloth netting. Twenty-five female houseflies, three to five days old, were introduced into the cage and the percent mortality was recorded after 48 hours. The LD₅₀ values are expressed in terms of μ g. per 25 female flies. The results of this insecticidal evaluation test are given in Table II under HF.

In the lygus bug (LB) *Lygus hesperus* test, ten to twenty-five two-week old nymphs of lygus bug were placed in separate circular cardboard cages sealed on one end with cellophane and covered by a cloth netting on the other. Aliquots of the toxicants, dissolved in an appro-

priate solvent, were diluted in water containing 0.002% of a wetting agent, Sponto 221® (polyoxyether of alkylated phenols blended with organic sulfonates). Test concentrations ranged from 0.05% downward to that at which 50% mortality was obtained. Each of the aqueous suspensions of the candidate compounds were sprayed onto the insect through the cloth netting by means of a hand-spray gun. Percent mortality in each case recorded after 24 and 72 hours counts were made to determine living and dead insects. The LD-50 values expressed as percent of toxicant in the aqueous spray were calculated and recorded. These values are reported under the column LB in Table II.

The insect species black bean aphid (BA) *Aphis fabae* (Scop.) was also employed in the test for insecticidal activity. Young nasturtium (*Tropaeolum* sp.) plants, approximately 2 to 3 inches tall, were used as the host plants for the bean aphid. The host plant was infested with approximately 50-75 of the aphids. The test chemical was dissolved in acetone, added to water which contained a small amount of Sponto 221®, an emulsifying agent. The solution was applied as a spray to the infested plants. Concentrations ranged from 0.05 percent downward until an LD-50 values was achieved. These results are given in Table II under the column BA.

ACARICIDAL EVALUATION TEST

The two-spotted mite (2SM), *Tetranychus urticae* (Koch), was employed in tests for miticides. Young pinto bean plants or lima bean plants (*Phaseolus* sp.) in the primary leaf stage were used as the host plants. The young pinto bean plants were infested with about 100 mites of various ages. Dispersions of candidate materials were prepared by dissolving 0.1 gram in 10 ml. of a suitable solvent, usually acetone. Aliquots of the toxicant solutions were suspended in water containing 0.002% v./v. Sponto 221®, polyoxyethylene ether sorbitan monolaurate, an emulsifying agent, the amount of water being sufficient to give concentrations of active ingredient ranging from 0.05% to that at which 50% mortality was obtained. The test suspensions were then sprayed on the infested plants to the point of run off. After 7 days, mortalities of the post-embryonic form was determined. The percentage of kill was determined by comparison with control plants which had not been sprayed with candidate compounds. The LD-50 value was calculated using well-known procedures. These values are reported under the columns 2SM-PE and 2SM-Eggs, in Table II.

SYSTEMIC EVALUATION TEST

This test evaluates the root absorption and upward translocation of the candidate systemic compound. The bean aphid (BA) *Aphis fabae* (Scop.) was employed in the test for systemic activity.

Young nasturtium plants were used as the host plants for the bean aphid. The host plants were transplanted into one pound of soil that had been treated with the candidate compound. Immediately after planting in the treated soil, the plants were infested with the aphids. Concentrations of toxicant in the soil ranged from 10 p.p.m. per pound of soil downward until an LD-50 value was obtained. Mortality was recorded after 72 hours.

The percentage of kill of the test species was determined by comparison with control plants placed in distilled water or untreated soil. The LD-50 values were calculated. These systemic test results are reported in Table II under the column BA-SYS.

TABLE II

Compound number	HF, $\mu\text{g}/25\%$	LB, percent	BA, percent	BA-sys, p.p.m.	2SM, percent	
					PE	Eggs

NOTE.—(—indicates not tested for the indicated insect species.)

The candidate compounds were also tested as systemic toxicants against two-spotted mite according to the following procedure.

Aliquots of the toxicant dissolved in an appropriate solvent are diluted in water and placed in glass bottles. Concentrations of active ingredient range from 10 p.p.m. to that at which 50% mortality is obtained. Pinto bean (*Phaseolus* sp.) plants with expanded primary leaves are placed in the solution so that the roots and major portions of the stem are completely immersed. Immediately after, the leaves are infested with 75-100 mites of various ages. Mortality of adults, nymphs and eggs is recorded after one week, and LD-50 values are expressed as parts per million (p.p.m.) of toxicant in the aqueous suspensions.

Some of the results as a systemic toxicant against two-spotted mite, can be summarized as follows: Compound No. 1, LD-50: 10 p.p.m.; and Compound No. 2, LD-50: 1 p.p.m.

As those in the art are well aware, various techniques are available for incorporating the active component or toxicant in suitable pesticidal compositions. Thus, the pesticidal compositions can be conveniently prepared in the form of liquids or solids, the latter preferably as homogeneous free-flowing dusts commonly formulated by admixing the active component with finely divided solids or carriers as exemplified by talc, natural clays, diatomaceous earth, various flours such as walnut shell, wheat, soya bean, cottonseed and the like.

Liquid compositions are also useful and normally comprise a dispersion of the toxicant in a liquid media although it may be convenient to dissolve the toxicant directly in a solvent such as kerosene, fuel oil, xylene, alkylated naphthalenes or the like and use such organic solutions directly. However, the more common procedures is to employ dispersions of the toxicant in an aqueous medium and such compositions may be produced by forming a concentrated solution of the toxicant in a suitable organic solvent followed by dispersion in water, usually with the aid of surface active agents. The latter, which may be anionic, cationic or nonionic types, are exemplified by sodium stearate, potassium oleate and other alkaline metal soaps and detergents such as sodium lauryl sulfate, sodium naphthalene sulfonate, sodium alkyl naphthalene sulfonate, methyl cellulose, fatty alcohol ethers, polyglycol fatty acid esters, and other polyoxyethylene surface active agents. The proportion of these agents commonly comprises 1-15% by weight of the pesticidal compositions although the proportion is not critical and may be varied to suit any particular situation.

What is claimed is:

1. A compound of the formula

in which R is hydrogen or alkyl having 1 to 5 carbon atoms, inclusive; R₁ is hydrogen or alkyl having 1 to 5 carbon atoms, inclusive; R₂ is alkyl having 1 to 5 carbon atoms, inclusive, or alkoxy having 1 to 5 carbon atoms, inclusive; R₃ is alkoxy having 1 to 5 carbon atoms, inclusive; R₄ is alkyl having 1 to 5 carbon atoms, inclusive, alkenyl having 3 to 6 carbon atoms, inclusive, alkynyl having 3 to 6 carbon atoms, inclusive, benzyl, or carbamoyloxyalkylene, wherein said alkylene has 1 to 3 carbon atoms, inclusive.

2. A compound according to claim 1 in which R is hydrogen, R₁ is hydrogen, R₂ is alkoxy having 1 to 5 carbon atoms, inclusive, R₃ is alkoxy having 1 to 5 carbon atoms, inclusive, and R₄ is alkyl having 1 to 5 carbon atoms, inclusive.

3. The compound according to claim 2 in which R₂ is ethoxy, R₃ is ethoxy and R₄ is methyl.

4. The compound according to claim 2 in which R₂ is methoxy, R₃ is methoxy and R₄ is methyl.

5. A compound according to claim 1 in which R is hydrogen, R₁ is hydrogen, R₂ is alkyl having 1 to 5 carbon atoms, inclusive, R₃ is alkoxy having 1 to 5 carbon atoms, inclusive, and R₄ is alkyl having 1 to 5 carbon atoms, inclusive.

6. The compound according to claim 5 in which R₂ is ethyl, R₃ is ethoxy and R₄ is methyl.

7. The compound according to claim 5 in which R₂ is ethyl, R₃ is isopropoxy and R₄ is methyl.

8. The compound according to claim 5 in which R₂ is methyl, R₃ is methoxy and R₄ is methyl.

9. The compound according to claim 5 in which R₂ is ethyl, R₃ is methoxy and R₄ is methyl.

10. The compound according to claim 5 in which R₂ is ethyl, R₃ is isopropoxy and R₄ is n-propyl.

11. A compound according to claim 1 in which R is alkyl having 1 to 5 carbon atoms, inclusive, R₁ is hydrogen, R₂ is alkoxy having 1 to 5 carbon atoms, inclusive, R₃ is alkoxy having 1 to 5 carbon atoms, inclusive, and R₄ is alkyl having 1 to 5 carbon atoms, inclusive.

12. The compound according to claim 11 in which R is methyl, R₂ is ethoxy, R₃ is ethoxy and R₄ is methyl.

13. A compound according to claim 1 in which R is alkyl having 1 to 5 carbon atoms, inclusive, R₁ is alkyl having 1 to 5 carbon atoms, inclusive, R₂ is alkoxy having 1 to 5 carbon atoms, inclusive, R₃ is alkoxy having 1 to 5 carbon atoms, inclusive and R₄ is alkyl having 1 to 5 carbon atoms, inclusive.

14. The compound according to claim 13 in which R is methyl, R₁ is methyl, R₂ is ethoxy, R₃ is ethoxy and R₄ is methyl.

15. A compound according to claim 1 in which R is alkyl having 1 to 5 carbon atoms, inclusive, R₁ is alkyl having 1 to 5 carbon atoms, inclusive, R₂ is alkyl having 1 to 5 carbon atoms, inclusive, R₃ is alkoxy having 1 to 5 carbon atoms and R₄ is alkyl having 1 to 5 carbon atoms, inclusive.

16. The compound according to claim 15 in which R is methyl, R₁ is methyl, R₂ is ethyl, R₃ is ethoxy and R₄ is ethyl.

17. The compound according to claim 15 in which R is methyl, R₁ is methyl, R₂ is ethyl, R₃ is isopropoxy and R₄ is methyl.

18. The compound according to claim 15 in which R is methyl, R₁ is methyl, R₂ is ethyl, R₃ is isobutyl and R₄ is methyl.

19. A compound according to claim 1 in which R is hydrogen, R₁ is hydrogen, R₂ is alkoxy having 1 to 5 carbon atoms, inclusive, R₃ is alkoxy having 1 to 5 carbon atoms, inclusive and R₄ is alkenyl having 3 to 6 carbon atoms, inclusive.

20. The compound according to claim 19 in which R₂ is methoxy, R₃ is methoxy and R₄ is 2-propenyl.

21. A compound according to claim 1 in which R is hydrogen, R₁ is hydrogen, R₂ is alkyl having 1 to 5 carbon atoms, inclusive, R₃ is alkoxy having 1 to 5 carbon atoms, inclusive and R₄ is alkenyl having 3 to 6 carbon atoms, inclusive.

22. The compound according to claim 21 in which R₂ is ethyl, R₃ is isopropoxy and R₄ is 2-propenyl.

23. The compound according to claim 21 in which R₂ is ethyl, R₃ is ethoxy and R₄ is 2-propenyl.

24. The compound according to claim 21 in which R₂ is ethyl, R₃ is methoxy and R₄ is 2-propenyl.

25. A compound according to claim 1 in which R is hydrogen, R₁ is hydrogen, R₂ is alkyl having 1 to 5 carbon atoms, inclusive, R₃ is alkoxy having 1 to 5 carbon atoms, inclusive, and R₄ is alkynyl having 3 to 6 carbon atoms, inclusive.

26. The compound according to claim 25 in which R₂ is ethyl, R₃ is ethoxy and R₄ is 2-propynyl.

27. The compound according to claim 25 in which R₂ is ethyl, R₃ is isopropoxy and R₄ is 2-propynyl.

28. The compound according to claim 25 in which R₂ is ethyl, R₃ is methoxy and R₄ is 2-propynyl.

29. The compound according to claim 25 in which R₂ is ethyl, R₃ is isobutoxy and R₄ is 2-propynyl.

30. A compound according to claim 1 in which R is hydrogen, R₁ is hydrogen, R₂ is alkoxy having 1 to 5 carbon atoms, inclusive, R₃ is alkoxy having 1 to 5 carbon atoms, inclusive and R₄ is benzyl.

31. The compound according to claim 30 in which R₂ is ethoxy and R₃ is ethoxy.

32. A compound according to claim 1 in which R is hydrogen, R₁ is hydrogen, R₂ is alkyl having 1 to 5 carbon atoms, inclusive, R₃ is alkoxy having 1 to 5 carbon atoms, inclusive, and R₄ is benzyl.

33. The compound according to claim 32 in which R₂ is ethyl and R₃ is ethoxy.

34. The compound according to claim 32 in which R₂ is ethyl and R₃ is isopropoxy.

35. The compound according to claim 32 in which R₂ is ethyl and R₃ is isobutoxy.

36. A compound according to claim 1 in which R is hydrogen, R₁ is hydrogen, R₂ is alkyl having 1 to 5 carbon atoms, inclusive, R₃ is alkoxy having 1 to 5 carbon atoms, inclusive, and R₄ is carbamoyloxyalkylene wherein said alkylene has 1 to 3 carbon atoms, inclusive.

37. The compound according to claim 36 in which R₂ is ethyl, R₃ is isopropyl and R₄ is N-methylcarbamoyloxyethylene.
